UNITED STATES PATENT OFFICE.

JOHN F. WHITE, OF CHICAGO, ILLINOIS, ASSIGNOR TO WHITE PRODUCTS COMPANY, OF CHICAGO, ILLINOIS, A CORPORATION OF ILLINOIS.

DESIGN FOR AN AUTOMOBILE RADIATOR CAP.

Application filed June 13, 1925. Serial No. 13,770. Term of patent 14 years.

To all whom it may concern:

Be it known that I, JOHN F. WHITE, a citizen of the United States, residing at Chicago, in the county of Cook and State of Illinois, have invented a new, original, and ornamental Design for an Automobile Radiator Cap, of which the following is a specification, reference being had to the accompanying drawings, forming a part hereof.

In the drawing,

Fig. 1 is a front elevation of an automobile radiator cap embodying the present design; and

Fig. 2 is a top view of the same.

I claim:

The ornamental design for an automobile radiator cap substantially as shown.

JOHN F. WHITE.
